CLAIM

I claim the ornamental design for a rear vehicle window vent visor, substantially as shown.

DESCRIPTION

FIG. 1 is a front perspective view of the rear vehicle window vent visor.

FIG. 2 is a rear perspective view of the rear vehicle window vent visor.

FIG. 3 is a front view of the rear vehicle window vent visor.

FIG. 4 is a rear elevation view of the rear vehicle window vent visor.

FIG. 5 is a left end view of the rear vehicle window vent visor.

FIG. 6 is a right end view of the rear vehicle window vent visor.

FIG. 7 is a top plan view of the rear vehicle window vent visor; and,

FIG. 8 is a bottom plan view of the rear vehicle window vent visor.
